UNITED STATES PATENT OFFICE.

ARTIMUS C. GAINES, OF PORTLAND, OREGON.

VALVE.

Application filed August 12, 1926. Serial No. 128,795.

This invention aims to provide a novel means whereby a back flow of cold water through the delivery pipe of a hot water tank may be prevented.

5 It is within the province of the disclosure to improve generally and to enhance the utility of devices of that type to which the invention appertains.

With the above and other objects in view 10 which will appear as the description proceeds, the invention resides in the combination and arrangement of parts and in the details of construction hereinafter described and claimed, it being understood that 15 changes in the precise embodiment of the invention herein disclosed, may be made within the scope of what is claimed, without departing from the spirit of the invention.

In the drawings:—

20 Figure 1 shows in elevation, a device constructed in accordance with the invention;

Figure 2 is a longitudinal section of the nozzle and attendant parts;

25 Figure 3 is a transverse section taken about on the line 3—3 of Figure 2;

Figure 4 is a longitudinal section of the nozzle.

The numeral 1 marks a hot water tank. The numeral 2 designates a looped conduit 30 in which a heater 7 is interposed. One end 3 of the looped conduit is connected to the bottom of the tank 1. The other end 4 of the looped conduit is connected to the top of the tank. Water is supplied to the bottom of the tank 1 through a pipe 5. A hot water delivery pipe 6 is branched off from the pipe 2. The numeral 8 designates a faucet controlling the flow of water through the delivery pipe 6.

40 Considering the device as above described, when the faucet 8 is opened to draw hot water, hot water flows downwardly in the pipe 2 from the top of the tank, and through the pipe 6, as is shown by the arrow 9. It

45 happens, however, that water is drawn through the lower part of the pipe 2, and through the heater 7, in the direction marked by the arrows 10. The result is that cold water flows either from the bottom of the

50 tank 1, or from the pipe 5, or from both of these sources, and mingles with the water passing through the pipe 6, in the direction of the arrow 9, the water delivered through the faucet 8 being cooled off, the heater 7

55 being inadequate to raise the temperature of the water which flows in the direction of the

arrows 10 through the pipe 6 and the faucet 8.

Having thus described the general construction of the device with which the present invention is to be used, and having 60 pointed out the disadvantages to be overcome, let consideration be given to those features of the invention which are shown in Figures 2, 3 and 4.

The casing 11 is mounted by threading or 65 otherwise, as at 12, in the bottom of the tank 1, and the pipe 5 is mounted, as at 14, in one side of the casing 11, the pipe communicating with the casing. In the lower end of the casing 11 there is a conical seat 70 15. A cap 16 is threaded on the lower end of the casing 11 and has an opening 17. Within the casing 11 is located a nozzle 18, the nozzle having a conical portion 19 received in the seat 15, the butt of the nozzle 75 being cylindrical, and being marked by the numeral 20, the butt having an outstanding shoulder 21. The butt 20 of the nozzle extends through the opening 17 in the cap 16, and the cap cooperates with the shoulder 21 80 to hold the conical part 19 of the nozzle firmly engaged in the seat 15. Near to its upper end, and within the casing 11, the nozzle 18 has outwardly slanting openings 22. The adjacent end of the casing 11 is 85 flared in its bore, as shown at 23. The end of the nozzle 18 is closed by a deflector 24, the undersurface of which is beveled off, as at 25, to cooperate with the flared portion 23 of the bore of the casing. The end 3 of 90 the looped pipe 2 is threaded into the butt 20 of the nozzle.

The cold water, passing through the pipe 5, enters the casing 11, and moves upwardly about the nozzle 18. As the cold water 95 passes by the inclined openings 22, there is a tendency to draw the water through the nozzle 18, from the pipe 2, in the direction of the arrows which are marked at 26. The result is that when the faucet 8 is open, to 100 draw hot water, hot water will be secured, from the top of the tank, there being no back flow in the direction of the arrows 10, to cause the cold water to enter the pipe 6 and to mingle with water which is flowing in 105 the direction of the arrow 9.

What is claimed is:—

In a device of the class described, a casing having an open end, a nozzle within the casing and extended at one end beyond the 110 open end of the casing, said end of the nozzle being closed and being provided with a

lateral deflector spaced from the open end of the casing but located in the path of fluid passing through the open end of the casing, the nozzle being provided with openings 5 located closely adjacent to the open end of the casing and disposed at an acute angle to the axis of the nozzle so as to discharge laterally and outwardly into the casing near to the open end thereof, an inlet for the nozzle and an inlet for the casing, the open end 10 of the casing having a flared mouth, and the deflector having an inclined edge surface disposed approximately parallel to the wall of the mouth.

In testimony that I claim the foregoing 15 as my own, I have hereto affixed my signature.

ARTIMUS C. GAINES.
